FREDERICK W. RUBIN AND HARRY E. RUBIN, OF INDIANAPOLIS, INDIANA; SAID HARRY E. RUBIN ASSIGNOR TO SAID FREDERICK W. RUBIN.

AUTOMATIC AND REMOTE HUMIDITY CONTROL.

Application filed October 30, 1922. Serial No. 597,909.

The object of this invention is to automatically and remotely control the temperature and relative humidity of lumber dry kilns or other buildings, rooms, compartments or tanks.

Heretofore in the art of lumber drying, the control devices have been exposedly positioned within the kiln, the operator manually regulating the temperature and humidity after entering the kiln and observing the indicating instruments. Such manual control was not only difficult but inaccurate wherefore, it is the object of this invention to automatically control the relative humidity by maintaining the same between certain limits which may be fixed by the operator at a convenient place and so associated with the recording device as to leave a record of the operation.

One feature of the invention resides in the use of a dry and wet recording thermometer apparatus with independent dry and wet extension tubes remotely positioned in the dry kiln, building, or compartment, said apparatus electrically controlling the heat supply means independently of the humidity line, as will be hereinafter more fully set forth and described.

The invention further contemplates the method of dry kiln operation, and the mechanism for controlling the same, which consists in repeatedly and alternately lowering and raising the relative humidity between certain limits so that when the instrument is once set the process will continue without requiring manual attendance and control, a record being made of the variation and the temperature control as well as the humidity control.

The full nature of the invention will be understood from the accompanying drawings and the following description and claims:

In the drawings Fig. 1 is a diagrammatic illustration of the invention applied to the outside wall of a compartment or dry kiln. Fig. 2 is an enlarged view of parts of the recording thermometer and controlling instrument. Fig. 3 is a section taken on line 3—3 of Fig. 2. Fig. 4 is a diagrammatic illustration of an instrument showing a

modified form having the recording device provided with both temperature and humidity control means. Fig. 5 is a top plan view of a compartment wall, showing the 55 thermometer tubes positioned within a compartment and the recording and controlling instruments positioned on the outside thereof. Fig. 6 is a perspective view showing a part of the control mechanism such is 60 illustrated in Figs. 1 to 3 inclusive. Fig. 7 is a sectional view of a portion of the control mechanism as employed in the modified structure illustrated in Fig. 4.

In the wood drying art it is essential that 65 the wood be dried under certain moisture conditions below which the dryness of the drying chamber seriously affects the surface of the wood in a manner known in the trade as case hardening. In order to control wood 70 drying, it must be borne in mind that the heat is the drying force while the moisture is the protective means for guarding against case hardening and the consequent splitting or checking of the lumber. The method 75 employed in this invention utilizes the drying means or heat in connection with the softening or decasing means such as steam or moisture through a suitable controlling mechanism.

As shown herein, there is a wall 10 of a dry kiln or other compartment in which it is desired to automatically regulate the heat and moisture or relative humidity. On the outside of the wall there are secured two 85 control devices, a recording dry thermometer 11 and a recording wet thermometer 12. From the thermometer 11, the tube 13 extends in the chamber or compartment and terminates in a temperature susceptible dry 90 bulb 113, and from the thermometer 12 another tube 14 extends into the compartment terminating in a wet bulb 114.

The dry recording thermometer is provided with an arcuate bar 16, extending from 95 the center of the instrument 11 to the circumference thereof and provided with certain graduations or numerals reading from end to end as from the center to the circumference. This arcuate bar has its center 100 of curvature at the pivotal mounting of an arm 17 which is influenced and moved about

its pivotal mounting by the expansion and contraction of a fluid in the tube 13 caused by the changes in temperature of the compartment. The detail mechanism whereby the expansion and contraction of the fluid in the tube 13 is transmitted to the arm 17, is illustrated in Fig. 6. It will be later described in detail.

The wet recording thermometer 12 is provided with a similar arm 117. The arm 17 as well as arm 117, is provided with a recording pen 17^b (Fig. 3) which is adapted to form a permanent record upon a recording sheet or chart 17^c carried upon the face of the instruments 11 and 12. The bars 16 and 116 (as shown in Figs. 2 and 3) are made of a nonconducting material provided with a metal wire or bar 21 extending longitudinally throughout the face thereof. On each of said bars there is slidably mounted a contact member 22 which is also formed of metal and remains in electrical contact with the metal bar 21 at all times, and is held in adjusted position by a set screw 23. The arcuate length of contact 22, as shown herein, is about 15°. The arms 17 and 117 are metallic and are of such length as to extend to a point adjacent the inner surface of the contact 22 so as to engage in contact therewith through the medium of the resilient fingers 17^a and 117^a. Thus, upon the arm 17 or 117 being moved by a variation in temperature or humidity to a position where the fingers 17^a or 117^a engage the contact 22, the circuit will be closed therethrough during such time as the respective arms move through an arc of substantially 15° to a point where the contact is disengaged by the finger whereupon the circuit will be broken.

The particular control mechanism for the compartment comprises the heat line 42 and moisture line 41, the heat line 42 is adapted to heat the compartment by steam passing through a closed coil or circulatory system while the moisture line 41 is adapted to discharge saturated steam into the compartment. The heat or dry steam line 42 is controlled by valve 43 which is maintained in normally closed position by a spring 143, but which may be opened against the tension of said spring by a solenoid 44. The moisture or wet steam line 41 is likewise controlled by the valve 40, which is normally maintained in closed position by a spring 140 and which is opened by the solenoid 38 against the tension of said spring. The valves 40 and 43 are accordingly closed through the action of their respective springs upon their relative solenoids being deenergized but on energizing of their respective solenoids they are open.

The solenoids 38 and 44 are independently controlled by a relay switch as will be further described. The main power lines

are connected to said solenoids as follows: A line 39 connects one terminal of the solenoid 38 with the line of the power supply. The other line of the power supply is connected by the wire 36 to the movable element 70 37 of a normally open switch. The stationary contact of said switch is connected by a line 136 with the other terminal of the solenoid 38, the spring 137 normally maintaining the switch element 37 in open position. Thus the valve 40 is in closed position as shown in Fig. 1 through the action of the spring 140 when the switch element 37 is held out of contact with the connection 136. But upon the solenoid 35 being 80 energized and the tension of the spring 137 overcome thereby, the circuit will be closed through the solenoid 38 and the valve 40 will be opened to permit wet steam or moisture to enter the kiln. 85

The solenoid 44 and, therefore, the valve 43 are somewhat similarly controlled. Herein a movable switch member 237 is normally maintained in closed position by the spring 337. The solenoid 44 is adapted, upon being energized to attract the member 237 and open the circuit in opposition to the spring 337. The normally closed switch member 237 is connected by the line 46 to one terminal of the solenoid 44, while the other terminal of the solenoid 44 is connected by the line 45 with one line of the main power supply. The contact made by the switch member 237 enclosing the circuit, is connected by the line 145 with the other line 90 of the main power supply.

Thus, when the relay or solenoid 34 is energized, the normally closed switch 237 is opened and the current is cut off from the solenoid 44 so as to cause the heat control valve 43 to be closed by the spring 143. Whenever the solenoid 34 is deenergized the switch 237 will close the circuit, thereby energizing the solenoid 44 and opening the valve for allowing dry steam to enter the 100 kiln. 110

The wiring connections between the temperature and humidity thermometers and the solenoids are as follows: The line 20 connects the outer end of the bars 16 and 116 and an extension 31 thereof connects with one terminal of the battery 30. The other terminal of the battery 30 is connected by the line 130 to one terminal of the solenoid 34. The other terminal of the solenoid 34 is connected by the line 32 to the arm 17. The line 32 is provided with a resistance R, and is also connected by the branch 132 to one terminal of the solenoid 35. Said resistance R is slightly greater than the total resistance of the line 33 and solenoid 35. The purpose of this resistance is to insure the solenoid 35 receiving current when the arm 17 engages the contact 22. Therefore, when both arms are in con- 115 120 125 130

tact it is immaterial which way the current is supplied to the solenoid 34. The other terminal of the solenoid 35 is connected by the line 33 to the arm 117.

Reference may now be had to Fig. 6 wherein the interior mechanism for controlling the arm 17 by means of the extension tube is illustrated in detail. To the extension tube, in this instance, the tube 13, there is connected a curved tube 101. Expansion of the heat susceptible fluid in tube 13 tends to deform the curved tubular portion 101 and such deformation is transmitted through the coil spring 102 suitably supported in the frame 100. A shaft 104 is also supported in said frame 100 and pivotally mounted on said shaft is the arm 17. One end of the arm 17 is connected to an angular extension 103 and the coil spring member 102. Suitable means, such as the adjusting screw 105, adjustably connects said arm and said extension together so that deformation of the extension tube 101 would be transmitted to the arm 17. The same mechanism is likewise employed for controlling the arm 117.

In Fig. 4 there is shown a modified form wherein both temperature and humidity arms are combined in a unitary structure, or in other words, both the humidity and temperature thermometers as shown separately in Fig. 1 are combined into one instrument as shown in Fig. 4. In this form, there are provided two arms, one arm being indicated by 217 and corresponding to the arm 17 above mentioned for indicating the temperature and the other arm indicated by 317, being that indicated in Fig. 1 as 117 for indicating the humidity. Said arms are pivotally mounted upon the same axis 51, one above the other so as to move independently of each other. To this structure there is added an arcuate bar 216 corresponding to the bars 16 and 116 above mentioned, upon which there are adjustably positioned the contact members 52 and 53 adapted to be engaged by the arms 217 and 317 respectively. Connected with each of the arms 217 and 317 there are independent extension tubes which extend into the dry kiln or compartment. The extension tube 213 is connected with the arm 217 and the tube 214 with the arm 317. The tubes 213 and 214 are provided at their inner ends with temperature susceptible bulbs such as 113 and 114 shown in Fig. 5.

In Fig. 7 there is illustrated the mechanism for operating the associated arms 217 and 317 as shown in Fig. 4, said arms being pivotally supported at 51 and connected with a coil spring substantially similar to that disclosed in Fig. 6. Thus, each of the coil members 102 in Fig. 7 is associated with an indicating arm as shown.

The wiring diagram employed in con-

nection with the construction shown in Fig. 4 is substantially the same as illustrated in Fig. 1, the only change being that the line 33 is replaced by the line 133, the line 32 by the line 132 and the line 31 by the line 131. In this construction the line 20 is omitted, since the same is unnecessary. It will further be noted that the line 132 is connected directly with the arm 217 and the line 133 directly with the arm 317, which are insulated from each other on their pivotal mounting 51.

The operation of the device is as follows, reference being had to Fig. 1. After the green wood is placed in the kiln, the contacts 22 upon the bars 16 and 116 are adjusted to the desired positions, and the contact finger 117^a, on the arm 117, is set to engage the contact 22 on the bar 116. When the main switch (not shown) in the main power line is closed the circuits are energized as follows: Since the finger 117^a is in engagement with the contact 22, both solenoids 34 and 35 will be energized, thereby closing the circuit through the switch 37, to supply energy to the solenoid 38 to open the valve 40 and supply wet steam to the compartment. At the same time the solenoid 34 is energized to open the circuit through switch 237, and thereby open the circuit through the solenoid 44. This deenergizes the same and permits the spring 143 to close the valve 43 in the dry steam line. The valves are thus alternately and oppositely or differentially operable. As the temperature is increased in the compartment or kiln, due to the heat in the wet steam, both arms 17 and 117 tend to travel from the center toward the periphery of the thermometer.

When arm 117 passes beyond contact 22 on bar 116 the wet steam is cut off. If arm 17 is not on contact 22 of bar 16 when this occurs the heat line immediately is opened. If arm 17 is on its contact the heat line is maintained closed until such time as the compartment cools. While such cooling occurs both arms reverse their travel with the fall in temperature therein and upon the finger 117^a engaging the contact 22 of the wet thermometer in its return travel, the wet steam will again be introduced into the compartment and the operation repeated. If the relative humidity is such that both fingers pass out of engagement with their contacts 22, the respective valve controlling circuits will be opened through the solenoids 34 and 35 and thereby permit the dry steam valve to be opened and the wet steam valve to be closed so as to supply dry steam to the compartment for heating purposes only. As the dry steam increases the temperature in the compartment, the humidity decreases and causes a cooling, due to evaporation of the wet bulb thermometer, thereby causing the wet bulb thermometer to trail the dry

thermometer but nevertheless rising therewith, showing that the change in humidity is expressed as a temperature change. When the finger 117^a again engages the contact 22 of the wet bulb thermometer, such engagement serves to cut off the dry steam and again supply wet steam to the kiln. Whenever the positions are such that both fingers pass the contacts 22, the dry steam line 42 will be open, thereby increasing the temperature. Such increased temperature will cause the wet bulb thermometer to trail due to evaporation, until the contact 117^a engages the contact 22 and again cuts out the dry steam line and energizes the wet steam line, thereby positively protecting the wood in the compartment against drying in a humidity which is exceedingly dangerous.

After the drying progresses, the duration 20 of the cycle gradually decreases since the amount of moisture derived from the wood is gradually becoming less. The heating period between successive saturating intervals will remain relatively constant. 25 This is because of the decrease in loss of temperature by evaporation. The saturating interval between successive heating intervals gradually decreases after the drying is continued, so that toward the end of the 30 drying period for which the temperature and relative humidity conditions have been adjusted, the interval of saturation gradually approaches the interval of heating so that both sides of the curve for the complete 35 cycle approach each other, whereas the initial cycle or cycles in any given point show a relatively steep drying interval and a relatively long and sloping saturating interval. Likewise the total interval for each cycle 40 gradually decreases during any given period.

After this cyclical performance has been repeated for the desired total interval, the contacts upon the wet and dry bulb thermometers may be manually readjusted for the subsequent drying period. These new limits and the intervals may be substantially those well known in the art, and which heretofore have been manually maintained. 50 The present invention maintains the desired limiting factors and prevents drying of the wood under adverse conditions.

From the foregoing, therefore, it will be understood that the drying is always accomplished in cycles and that after operation has been started and the contacts have been adjusted, there is an alternate and repeated raising and lowering of the temperature in the kiln accompanied simultaneously, as a rule, by a lowering and raising of the relative humidity. Thus drying may be accomplished as a forced return by utilizing heretofore considered excessive temperatures but these excessive temperatures as will be apparent from the foregoing, are injurious if

the relative humidity is such that the same does not take place for any excessive or dangerous interval. The invention disclosed herein assures that excessive temperatures may be utilized because the wood is always protected against excessive or injurious drying. The limits are those heretofore usually utilized. The present invention mechanically controls forced but non-injurious lumber drying, whereby the total 75 drying period is materially reduced.

It will be understood that the essential features of the invention consist in securing a permanent record of the conditions under which each batch of lumber was dried. 80 Second, the remote control of the conditions within the compartment. Third, the automatic protective arrangement whereby the wood can not be dried under humidity conditions which will damage the wood and, of course, the combination of these several features remains a most desirable construction for remotely controlling and recording the drying of the lumber.

The invention claimed is:

1. In a device for controlling the temperature and relative humidity in a compartment, the combination of dry and wet thermometer apparatus normally unexposed to the compartment but with independent extensions exposed therein, electrically operable means controlling the temperature and relative humidity in the compartment, and indicating means also normally unexposed to the compartment including a temperature responsive indicating arm and a bar co-operating therewith.

2. In a device for controlling the temperature and relative humidity in a compartment, the combination of a unitary wet and dry thermometer apparatus normally unexposed to the compartment but with independent extensions exposed therein, electrically operable means controlling the temperature and relative humidity in the compartment, and indicating means for each portion of said wet and dry apparatus also normally unexposed to the compartment including a temperature responsive indicating arm and a bar co-operating therewith.

3. In a device for controlling the temperature and relative humidity in a compartment, the combination of dry and wet thermometer apparatus normally unexposed to the compartment, but with independent extensions exposed therein, electrically operable means controlling the temperature and relative humidity in the compartment, and indicating and recording means also normally unexposed to the compartment including a temperature responsive indicating and recording arm and a bar co-operating therewith.

4. In a device for controlling the temperature and relative humidity in a compartment,

- ment, the combination of a unitary wet and dry thermometer apparatus normally unexposed to the compartment, but with independent extensions exposed therein, electrically operable means controlling the temperature and relative humidity in the compartment, and indicating and recording means for each portion of said wet and dry apparatus also normally unexposed to the compartment including a temperature responsive indicating and recording arm and a bar cooperating therewith. 5
5. A device for controlling the temperature and relative humidity in dry kilns, the combination of dry and wet thermometer apparatus unexposedly positioned with respect to the compartment and having independent extensions exposedly positioned to the relative humidity within said compartment, a bar mounted adjacent the thermometer apparatus, a contact adjustably mounted upon said bar and means operable by the thermometer apparatus for engaging and disengaging the contact for controlling the relative humidity within the compartment. 10
15. 6. In a device for controlling the temperature and relative humidity in a compartment, the combination of dry and wet thermometer apparatus, and electrically operable means controlling the temperature and relative humidity in the compartment for repeatedly and alternately raising and lowering the relative humidity of the air in said compartment. 20
25. 7. In a device for controlling the temperature and relative humidity in a compartment, the combination of dry and wet thermometer apparatus, and means actuated by said dry and wet thermometer apparatus for controlling the temperature and relative humidity in the compartment for repeatedly and alternately lowering and raising the relative humidity of the air in said compartment. 30
35. 8. In a device for controlling the temperature and relative humidity in a compartment, the combination of dry and wet thermometer apparatus, electrically operable means controlling the temperature and relative humidity in the compartment and indicating means including a temperature responsive indicating arm and a bar cooperating therewith. 45
40. 9. In a device for controlling the temperature and relative humidity in a compartment, the combination of dry and wet thermometer apparatus, electrically operable means controlling the temperature and relative humidity in the compartment for repeatedly and alternately raising and lowering the relative humidity of the air in said compartment, and means for adjusting the temperature of the air after the drying continues. 50
45. 10. In a device for controlling the temperature and relative humidity in a compartment, the combination of dry and wet thermometer apparatus, electrically operable means controlling the temperature and relative humidity in the compartment for repeatedly and alternately raising and lowering the relative humidity of the air in said compartment, and means for adjusting the relative humidity lower limit. 55
50. 11. In a device for controlling the temperature and relative humidity in a compartment, the combination of air humidifying means therefor, control means for said air humidifying means, and automatic means for operating said control means to produce alternate lowerings and raisings of the relative humidity of the air in said compartment. 60
55. 12. In witness whereof, we have hereunto affixed our signatures. 65
